CLAIM

The ornamental design for a shoulder supported carrying device, as shown and described.

DESCRIPTION

FIG. 1 shows a left side elevational view of a first embodiment of the design of the invention;

FIG. 2 shows a front elevation view with the rear being identical in appearance;

FIG. 3 shows a top plan view thereof;

FIG. 4 is a bottom plan view of the design of the first embodiment of the invention;

FIG. 5 shows a right side elevation view of the first embodiment of the invention;

FIG. 6 is a cross-section elevation view of the invention taken along section line 6—6;

FIG. 7 is a second embodiment of the design shown in FIG. 1;

FIG. 8 is a cross-section elevation view of FIG. 7 taken along section line 8—8;

FIG. 9 is a third embodiment of the design shown in FIG. 1; and,

FIG. 10 is a cross-section elevation view of FIG. 9 taken along section line 10—10.

The cross-hatched shading on the strap represents a cloth material and the contrasting material on the same strap represents a fastening material. The cross-hatched shading is understood to cover the entire surface indicated by the shading.

It will be appreciated that the alternate embodiment drawings, 8, 9 and 10 illustrate the differences between themselves and the first fully shown embodiment. All other views of the FIGS. 7, 8, 9 and 10 alternate embodiments are identical to those shown in the first embodiment.
